UNITED STATES PATENT OFFICE.

IRVING C. WOODWARD, OF CHICAGO, ILLINOIS.

TOY GUN.

No. 840,888.

Specification of Letters Patent.

Patented Jan. 8, 1907.

Application filed February 24, 1906. Serial No. 302,794.

To all whom it may concern:

Be it known that I, IRVING C. WOODWARD, a citizen of the United States of America, and a resident of Chicago, Cook county, State of Illinois, have invented certain new and useful Improvements in Toy Guns, of which the following is a specification.

The main object of this invention is to provide a simple, inexpensive, and improved structure for spring-guns. This object is accomplished by the device shown in the accompanying drawings, in which—

Figure 1 is a side elevation of a spring-gun constructed according to this invention, the various parts being in the position which they would occupy before the gun is loaded. Fig. 2 is a side elevation showing the parts in position for discharging a projectile. Fig. 3 is a top plan of the same. Fig. 4 is a detail showing the shape of the blank from which the trigger portion of the gun is formed.

In the construction shown, the barrel and handle or stock of the gun are integral and formed of a single piece of wire rod. This rod is straight throughout the portion which forms the barrel 1 and is bent to form a closed loop or handle 2 at the rear end of the barrel. The end 3 of the rod is at the formed part of the loop and is disposed substantially at right angles to the barrel.

The trigger member consists of a flat strip 4 of metal, having perforations 5, 6, 7, and 8 of different sizes, as shown in Fig. 4. The end 9 of the strip 4 is bent upward at the middle of the perforation 6. The perforation 5 encircles the straight portion of the barrel 1, and the bent portion at the sides of the aperture 6 straddles the rear part of the loop 2. The forward part 3 of the loop passes upwardly through the perforation 7. The perforation 5 is slightly elongated, so as to permit the piece 4 to swing between the positions shown in Figs. 1 and 2. The portions of the loop 2 and 3, which respectively pass through the slot 6 and the perforation 7, guide the movement of the trigger member and prevent it from shifting sidewise. The strip 4 is doubled upon itself to form the trigger at 10 and is also bent upward at 11, so that the portions thereof which lie at the sides of the slot 8 will form an upwardly-extending forked detent which straddles the barrel 1. The edge 17 of that portion of the strip 4 which lies between the apertures 5 and 6 bears against the part 2 of the handle and forms the fulcrum about which the trig-

ger member rotates. The part 9 extends upward and forward and forms the shoulder against which the spring 12 bears. The apertures 5 and 7 are long enough to permit the trigger member to swing on its fulcrum 17.

The helical spring 12 encircles the barrel 1, and its rearward end 13 is fastened at the perforation 5 to the end 9 of the strip 4. The projectile which this gun is adapted to discharge is a tubular ball 15, which may be slid over the barrel 1 against the action of the spring 12, being then held in position by the shoulders 16 on the trigger member. The part 14 of the trigger member extends downward at an angle and serves to push the trigger out of the way when the ball is being pushed along the barrel in loading the gun.

The operation of the device shown is as follows: The ball 15 is passed over the end of the barrel and slid along until the spring has been compressed. The inclined part 14 causes the trigger member to shift out of the way to permit the ball to pass behind the shoulders 15. The pressure of the spring 12 upon the part 9 then causes the trigger member to swing on its fulcrum and bring the shoulders 15 into position for holding the ball in the loaded position with the spring compressed. When the trigger 10 is now pulled toward the handle, the trigger member will swing downward, releasing the ball from the shoulders 15 and permitting the same to be projected forward by the spring 12.

What I claim as my invention, and desire to secure by Letters Patent, is—

1. A toy gun comprising a rod having a straight portion forming the barrel of the gun and being bent to form a handle at one end of the barrel, a helical spring encircling said barrel, and a trigger member fulcrumed on said rod and having a forked part adapted to straddle the barrel in front of the spring to secure the same after it has been compressed.

2. A toy gun comprising a rod having a straight portion forming the barrel of the gun and being bent to a loop to form a handle at one end thereof, a helical spring encircling the barrel, and a trigger member movably mounted on said rod and having apertures therein for receiving the rod at opposite sides of the loop for guiding the movement of said member, said member being movable into and out of position for holding the spring in a retracted position.

3. A toy gun comprising a rod having a straight portion to form the barrel and being

- bent to a loop to form a handle at one end thereof, said loop having a portion at the forward side thereof disposed substantially at right angles to the barrel, a helical spring encircling the barrel, and a trigger member fulcrumed on said rod near the rear side of the loop and having an aperture fitting said forward portion to guide the movement of the trigger member, and said member having a forked part adapted to straddle the barrel for holding said spring in its retracted position.
4. A toy gun comprising a rod having a straight portion forming the barrel and being bent to a loop to form a handle at one end thereof, a helical spring encircling the barrel, and a trigger member formed of a single strip of flat metal perforated for receiving the rod at opposite sides of said loop for securing said member to the barrel and permitting a limited transverse movement thereon, said strip being bent upward at its forward end to form a detent adapted to hold said spring in a retracted position.
5. A toy gun comprising a rod having a straight portion forming the barrel and being bent to a loop to form a handle at one end thereof, a helical spring encircling the barrel and a trigger member formed of a flat strip of metal perforated for receiving the rod at opposite sides of said loop for securing said member to the barrel and permitting a limited transverse movement thereon, said strip being slotted near its forward end and being bent upward at the slot to form a forked portion adapted to straddle the barrel and secure the spring in a retracted position.
6. A toy gun comprising a rod having a straight portion forming the barrel and being bent to a loop to form a handle at one end thereof, a helical spring encircling the barrel, and a trigger member formed of a single flat strip of metal perforated for receiving the rod at opposite sides of said loop for securing said trigger to the barrel and permitting a limited transverse movement thereof, said strip being bent upon itself to form a downwardly-extending trigger in front of the loop and being slotted at its forward end, the slotted portion of said strip being bent up-

ward to form a fork adapted to straddle the barrel for holding the spring in its retracted position, and the portion of said strip which is in front of said fork being inclined forward and downward to cause the fork to be pushed out of the way when a perforated projectile is pushed along the barrel for compressing the spring.

55

7. A toy gun comprising a barrel having a handle at one end, a helical spring encircling said barrel, and a trigger member having thereon a shoulder adapted to hold said spring in a retracted position, said trigger member having a part engaged by said spring and adapted through the pressure thereof to urge said shoulder into position for securing the spring.

60

8. A toy gun comprising a barrel having a handle at one end, a helical spring arranged for discharging a projectile along said barrel, and a trigger member having thereon a shoulder adapted to hold said spring in its retracted position, said trigger member having a part engaged by said spring and adapted through the pressure thereof, to urge said shoulder into position for securing the spring.

70

9. A toy gun comprising a rod having a straight portion to form the barrel and being bent to a loop at one end to form a handle, a helical spring encircling said barrel, and a trigger member formed of a single strip being perforated for receiving the rod at the front of said loop, being slotted and bent upon itself to form a fulcrum and fork engaging the rear part of said loop, the rearward end of said strip extending forward and upward from the fulcrum and having a perforation for receiving the barrel, the front end of said strip being bent up to form a shoulder for holding said spring in a retracted position, and said spring being adapted when compressed to bear upon the rear end of said trigger member and urge the front end thereof into position for engaging the spring.
